UNITED STATES PATENT OFFICE.

CHARLES L. WEIL, OF PORT HURON, MICHIGAN.

CLOSURE FOR DISCHARGE-APERTURES IN PACKAGES.

1,268,901.

Specification of Letters Patent. Patented June 11, 1918.

Application filed January 8, 1916. Serial No. 70,902.

To all whom it may concern:

Be it known that I, CHARLES L. WEIL, a citizen of the United States of America, residing at Port Huron, in the county of St. 5 Clair and State of Michigan, have invented certain new and useful Improvements in Closures for Discharge-Apertures in Packages, of which the following is a specification, reference being had therein to the accompanying drawings.

The invention relates to packages designed for holding granular material, such as salt, and it is the object of the invention to provide a simple form of closure for an 15 aperture in said package which may be readily opened for discharging the contents. It is a further object to facilitate the pouring of the granular material by a construction of closure which when open directs the 20 stream vertically downward and prevents a lateral overthrow. With these and other objects in view the invention comprises the construction as hereinafter set forth.

In the drawings:

25 Figure 1 is a perspective view of a box or carton provided with my improved form of closure, shown in open position;

Fig. 2 is a cross section showing the closure in closed position;

30 Fig. 3 is a similar view in open position;

Fig. 4 is a longitudinal sectional perspective view through the closure and adjacent portions of the receptacle;

35 Fig. 5 is a plan view of the receptacle showing the aperture therein with the closure removed;

Fig. 6 is a section illustrating the pouring of the material from the receptacle directed by the closure; and

40 Fig. 7 is a perspective view of the closure detached.

A is the box or receptacle having formed therein the discharge aperture B, which is shown as arranged in the cover of the box 45 near the periphery thereof. This aperture is preferably of substantially rectangular form, being provided at one end with an inwardly-projecting tongue portion C separated by slits D from the adjacent side portions. E is the closure preferably formed of sheet-metal and of a substantially U-shaped cross section, being provided with a flat top F having a projecting lip G at one end, and depending sides H. The latter are of triangular form having curved or segmental 55 ends I and at the opposite ends having

tongues J projecting beyond the end of the top portion F. These wings H are also preferably provided with laterally-deflected flange portions K at their lower ends, as 60 shown in Fig. 7. The closure E is so proportioned that the sides H will fit within the aperture B, the tongues J being first inserted and hooked under the cover at the ends of the slots D. The end of the top 65 section F will lie over the tongue C and the opposite end having the outwardly-curved lip G, as shown, will overlap the opposite end of the aperture B. To first engage the closure the sides H which are slightly resili- 70 ent are sprung inward enough to pass the laterally-deflected flanges K within the aperture, and upon releasing the pressure these sides will spring outward so that the flanges K will form stops preventing disengagement 75 of the sides.

With the construction as described the top portion G of the closure normally lies flat upon the cover of the box overlapping the ends of the aperture B, and its sides 80 fitting tightly against the sides of the aperture, thereby forming a tight fit. The friction is sufficient to hold the parts in this position even where the box A is inverted. To open the closure, by engaging the finger nail 85 beneath the projecting lip G of the closure E the latter may be raised until the stops K prevent further movement. The material may then be poured from the box, as shown in Fig. 6, the closure forming a deflector 90 which prevents the stream from shooting out laterally and compels a vertical downward movement.

By reason of the projecting tongues J on the closure and the inwardly-projecting tongue C on the box cover a pivotal engagement is secured without bending or stressing the parts. The sides H may if desired be slightly concaved, as indicated at L, so as to relieve from friction during opening movement of the closure and at the same time maintaining a tight fit in closed and open positions.

What I claim as my invention is:

1. The combination with a receptacle having a pouring aperture in an end face thereof, adjacent the edge of said face, of a closure for said aperture pivotally engaged with the inner edge thereof, said closure being outwardly adjustable to a deflector forming position, and means limiting outward pivotal motion of the closure. 105 110

2. The combination with a receptacle having a pouring aperture in an end face thereof adjacent the edge of said face, a member having a flat top and depending sides, its inner end being pivotally engaged with the inner edge of said aperture, said member being adjustable from a closure forming to a deflector forming position, and means carried by said member engageable with the in-

ner surface of said apertured end to limit 10 outward pivotal movement.

In testimony whereof I affix my signature in presence of two witnesses.

CHARLES L. WEIL.

Witnesses:

JAMES P. BARRY,
PHYLLIS COBURN.
